FIG. 2

FIG. 3

INVENTOR
L. W. Andersen.

By Hull Smith Brock & West,
ATTYS.

UNITED STATES PATENT OFFICE.

LAURITZ W. ANDERSEN, OF WATERBURY, CONNECTICUT, ASSIGNOR TO PLUME AND ATWOOD MANUFACTURING COMPANY, OF WATERBURY, CONNECTICUT, A CORPORATION OF CONNECTICUT.

REFLECTOR CONNECTION.

1,170,596.

Specification of Letters Patent.

Patented Feb. 8, 1916.

Application filed August 25, 1915. Serial No. 47,214.

To all whom it may concern:

Be it known that I, LAURITZ W. ANDERSEN, a citizen of the United States, residing at Waterbury, in the county of New Haven 5 and State of Connecticut, have invented a certain new and useful Improvement in Reflector Connections, of which the following is a full, clear, and exact description, reference being had to the accompanying drawings.

This invention relates generally to portable electric fixtures and more particularly to devices employing reflectors or shades; and the object of the invention is to provide 15 a novel connection between the socket and reflector whereby certain advantageous results are obtained.

One much desired result obtained, is the centering of the incandescent lamp within 20 the reflector.

Another very advantageous result obtained, is the ability to turn the reflector freely upon the lamp and socket so the light can be thrown in any direction, and another 25 result obtained is the provision of a support for the lamp socket itself and at the same time provide a further connection for the reflector.

With these objects and results in view my 30 invention consists in the novel features of construction and arrangement, all of which will be fully described hereinafter and pointed out in the appended claims.

In the drawings forming a part of this 35 specification Figure 1 is a perspective view showing the practical application of my invention. Fig. 2 is a sectional view of the reflector and socket holding connection, and Fig. 3 is a detail perspective view partly in 40 section showing the parts detached.

It will be understood that this invention is capable of use in connection with any and all sorts of shades or reflectors to which a sleeve or neck can be attached, and in the 45 drawing I have shown one embodiment of my invention, and in which is illustrated a parabola reflector 10, having an opening 11 produced near one edge thereof to receive the incandescent lamp socket 12. A short 50 sleeve or neck 13, is fixed in this opening and extends outwardly as shown and is provided with an interior annular shoulder 14 preferably intermediate its ends. A socket holder, or socket receiving member 15, fits into this

sleeve or neck 13 and turns or rotates freely 55 therein; the inner end of said holder being flanged outwardly at 16, to engage and turn upon the interior shoulder 14, and an exterior bead 17, on the holder or member 15, engages the outer end of the sleeve 13, and thereby prevents longitudinal movement of 60 the holder within the sleeve, but permits the free and easy rotation thereof. This exterior bead 17 can be applied to the outside 65 of holder or can be rolled integral therewith as desired. This freely rotatable member 15, is intended to receive the ordinary incandescent lamp socket 12, and near its outer end is formed with an interior annular stop shoulder 18, against which the shoulder 19, 70 of the socket cap abuts when the socket is inserted in the socket holder or receiving member 15 thus properly positioning the said socket; and in practice we so dimension the sleeve or neck 13 and socket holder 15 75 that the lamp, will be centered in the reflector 10 when the socket or lamp is properly positioned and secured, and this centering of the lamp in the reflector is very advantageous in a device of this kind. 80

The holder 15 is slotted at 20, to accommodate the key of a key socket or the eyelet guide of a pull chain socket, and may of course, be omitted from holders intended to receive keyless sockets only. The outer end 85 of the socket holder is threaded as shown at 21, and for the purpose of securely fastening the lamp socket within the holder and supporting the same therein, I provide a flanged threaded ring 22, the flange thereof engaging 90 the shoulder 23 of the socket cap and the threaded portion engaging the threads 21 on the end of holder and binding said parts together.

Other forms of fastening means may be 95 employed to secure the socket in the holder, but the form illustrated is preferred on account of its simplicity and ease of manipulation.

The connection herein shown and described 100 properly positions the socket and lamp in the reflector, placing the lamp directly in the center of reflector; and the rotating connection enables one to turn the reflector at any desired angle with reference 105 to the lamp, and direct the light in any direction. Furthermore, the socket is positively supported within the holder by means

of the flanged clamping ring, and a firm connection provided for the reflector.

It will thus be seen that I provide an exceedingly simple and efficient reflector connection capable of carrying out all of the objects hereinbefore referred to.

Having thus described my invention, what I claim is:—

1. A reflector having an opening therein, a sleeve fitted in said opening, a socket holder fitting in said sleeve and turnable therein, the lower end of said socket holder being threaded and a flanged threaded ring adapted to engage the threaded end of the socket holder and maintain the socket therein.
2. A reflector having an opening therein, a sleeve fitted in said opening, said sleeve

having an interior annular shoulder, a socket holder fitted into said sleeve and having a flange at the inner end engaging said interior annular shoulder, the outer end of said socket holder being threaded and having an interior annular shoulder adjacent said threaded end, said holder having an exterior bead adapted to engage the outer end of sleeve, and a flanged threaded ring adapted to engage the threaded end of holder and maintain a socket therein.

In testimony whereof, I hereunto affix my signature in the presence of two witnesses.

LAURITZ W. ANDERSEN.
